VACUUM CLOSING MACHINE

Henry L. Guenther, Los Angeles, Calif.

Application October 24, 1931, Serial No. 570,928

14 Claims. (Cl. 113—82)

This invention relates to vacuum closing machines and particularly pertains to means for double seaming sanitary cans in vacua, as generally indicated in my co-pending application Serial No. 417,057, entitled "Vacuum double seaming machine", filed by me December 28, 1929.

In the operation of double seaming machines for applying caps to sanitary cans it is often desirable to withdraw the air from the cans so that the contents thereof may be sealed in vacua, and will thus be maintained in a sterile condition. In machines of this type it is necessary to provide means for introducing the cans and their caps into a vacuum chamber and to thereafter successively subject the cans to the action of first and second double seaming operations, which, in the present instance occur at separate seaming stations, and make it necessary for the machine to be intermittent in its operation. These operations necessitate the use of a rotary turret having complementary chucks between which the cans and caps may be positioned, and which turrets must be set into motion after each period of rest as represented by a double seaming operation, and must be brought to rest again prior to each successive double seaming operation. In the structure which is here shown the interval of movement represents a fraction of the complete rotation of the turret, making it necessary to accelerate and decelerate the movement of the turret rapidly. This has a tendency to place enormous objectionable strain upon the parts of the machinery and at the same time tends to impart violent motion to the contents of the can, often resulting in an objectionable "spilling", and in addition to the provision of numerous novel features of construction in a vacuum double seaming machine, it is a principal object of the present invention to move the unsealed and sealed cans through the machine with a minimum amount of violent action and disturbance to the contents of the cans, and at the same time bring about an acceleration and deceleration of the moving parts which will permit the parts to readily move during the acceleration period and to be cushioned against movement during the deceleration period of their cycle of operation.

It is a further object of the present invention to provide a novel mechanical movement whereby intermittent driving operation may be obtained by utilizing a differential Geneva movement, which makes it possible to accelerate or decelerate the driven member of the movement to any desired degree of speed within the limits

of the device, and at any point, or for any time interval during the intermittent operation.

The present invention broadly contemplates the provision of double seaming stations enclosed within a vacuum chamber, and to which chamber cans are delivered by novel feeding means and thereafter moved from point to point within the container upon a rotary turret, the turret and kindred parts being intermittently operated by a differential Geneva movement and the action of the turret being provided with damping means operating during the deceleration period only.

The invention is illustrated by way of example in the accompanying drawings, in which:

Fig. 1 is a view in plan showing the form of the present invention with a part of the structure removed to more clearly disclose the path of travel of the cans.

Fig. 2 is a view in front elevation showing the complete machine with the cover plates removed to disclose the two seaming stations and their relationship to the turret.

Fig. 3 is a view in vertical section and side elevation showing the co-relation of the driving elements of the machine.

Fig. 4 is a view in horizontal section through the machine as seen on the line 4—4 of Fig. 3, and disclosing the differential Geneva movement and the damping mechanism.

Fig. 5 is a fragmentary view in plan showing the differential Geneva movement with the parts in their position at a point midway the length of the operating stroke.

Fig. 6 is an enlarged view in vertical section through the differential Geneva movement as seen on the line 6—6 of Fig. 5.

Fig. 7 is an enlarged view in vertical section through the damping mechanism as seen on the line 7—7 of Fig. 4.

Fig. 8 is an enlarged fragmentary view in plan showing the star wheel for separately feeding the cans into the vacuum chamber and the arrangement of the feed floor.

Fig. 9 is a view in vertical section on the line 9—9 of Fig. 8 showing the variation in the thickness of the feed floor at the point of entry of the can to the vacuum chamber and the point of exit therefrom.

Fig. 10 is an enlarged fragmentary view in plan showing the structure by which the individual can pockets are drained in the event that they may contain an accumulated amount of moisture.

Fig. 11 is an enlarged view in vertical section

through one of the can pockets as seen on the line 11-11 of Fig. 10.

Fig. 12 is a view in vertical section through the star wheel and one of the drain pockets as seen on the line 12-12 of Fig. 10.

Fig. 13 is a view in diagram showing the developed length of the cam track 183 indicating the chuck elevating mechanism at the various stations therealong.

10 Fig. 14 is a view in plan showing the manner of obtaining an oil seal between the turret and its plate.

Fig. 15 is a diagrammatic view showing the vacuum manifold and its off-takes.

15 Referring more particularly to the drawings 10 generally indicates a can timing mechanism which delivers cans in spaced sequence to a positive feed device 11 which device in turn delivers cans to a feed plunger mechanism 12 by which 20 they are directly deposited in the pockets of a feed star wheel 14 and led into the housing of vacuum chamber 15 to be engaged and carried by a feed 25 turret 16 to successive first and second seaming stations 17 and 18.

25 The timing mechanism is of the general construction shown in Fig. 1 of the drawings, and includes a horizontally disposed disc 19 mounted upon a vertical shaft 20, upon which shaft is a feed cam 21 having a plurality of recesses 22 along the edge thereof for engaging the circumferential face of a can 23 and causing the can to roll along the yieldable feed fingers 24 until it rests within a recess 22 and is thus separated from a flow of cans and is equally spaced with 30 relation to a preceding can.

35 A can feed star wheel 25 is mounted to overhand the disc 19 and is carried on shaft 25'. This wheel has a plurality of fingers 26 by which the spaced cans are engaged and fed at a gradually accelerated speed along the arcuate guide 40 rails 27 and 28, and onto the horizontally moving conveyor chain 29, which forms a part of the can feed mechanism 11. The conveyor chain moves along between parallel floor plates 30 and 31, and is fitted with upstanding flights 32 which 45 will engage a can delivered on the chain and positively carry it forwardly into the machine.

50 The arcuate rails 27 and 28 continue in lengths 33 and 34 which are parallel to each other and parallel to the travel of the can. At the forward end of these rails they are curved to form arcuate portions 35 and 36 which cause the can to pursue a path of travel substantially radial to the axis of the timing shaft 37 upon which the star wheel 14 is mounted. The star wheel 14 is formed with a plurality of pockets here shown as four in number, each representing substantially half of a circle and into which pockets a can may move. By reference to Fig. 12 of the drawings it will be seen that these pockets are 55 inclined to the vertical and to their vertical axes. In that view the pocket is indicated at 39 and has parallel inclined sides 40 and 41. The side 40 is in advance of the can as it travels and the side 41 is in the rear of the can as it travels, this side being backed off as indicated at 42 to provide clearance for the flanged can top 43 which has been temporarily clinched onto the curl of the can body and is of larger diameter 60 than the can.

65 The can 23 is pushed into a pocket 39 by a pusher 44 which is a part of the mechanism previously indicated at 12. This pusher has a pad formed with an inclined face 45 substantially tangent to the edge of the can and at an 70 inclination to the path of reciprocal movement

of the pusher, and a shoulder 46 which is at right angles to that path. The pad 45 is carried upon a pusher rod 47 and reciprocably mounted in a guide bearing 48. The means for operating the same will be hereinafter described.

5 As the star wheel 14 rotates with the can delivered by the pusher it will travel over an arcuate floor section 49. This section is indicated in Figs. 1, 8 and 9, inclusive. After a can has been carried through the machine it is again delivered to the star wheel 14 upon the opposite side from its point of entry, and passes outwardly over an arcuate floor plate 50 disposed upon diametrically opposite sides of the axis of the star wheel.

10 For reasons to be hereinafter set forth, the vertical thickness of the plate 49 is substantially twice that of the thickness of the plate 50.

15 As previously stated, the star wheel 14 is placed to serve the double purpose of a feed gate into the vacuum chamber 51 enclosed by the housing 15, and out of this vacuum chamber after the double seaming operation has been completed. The vacuum chamber housing includes a vertical rear wall 52 directly in front of the star wheel 14, a removable front wall or door 53 parallel to the rear wall, side walls 54 and 55, a top 20 56 and a floor 57. The floor 57 is of material importance in the present instance in that it is formed with a plurality of openings here shown as four in number. One of these openings indicated at 58 provides a passageway through which a can may be introduced into the machine. Another opening 59 provides a passageway through 25 which the can may be partially elevated and disposed in operative relation to the seaming mechanism of the first seaming head 17. An adjacent opening 60 provides a passageway through which the can may be properly elevated into operative 30 relation to the second seaming head, and the final opening 61 provides a passageway through which the can may be ejected from the turret and subsequently removed from the machine.

35 The openings 58 and 61 which occur through the floor are on the outside of the vacuum chamber. The openings 59 and 60 are within the vacuum chamber.

40 Disposed beneath the floor 57 and having a flat face provided with a running fit thereagainst is a turret sealing plate 62 which is formed with a series of openings adapted to successively register with the four openings previously described as being formed through the floor 57. In the present instance the various openings have been so spaced as to make it possible for seven turret 45 openings to be formed and to properly register with the openings in the floor as the turret is intermittently rotated during its operation.

45 The turret openings indicated at 63 are each formed with a circumscribing cylindrical flange 64, shown particularly in Figs. 11 and 12. This flange is counterbored along its outer face as indicated at 65, and receives the circular lip 66 of a vacuum cylinder 67 which is secured to the flange 64 by cap screws 68. The diameter of the 50 openings 63 and the internal diameter of the cylinders 67 are equal and of sufficient size to permit the can 23 to freely pass in and out of the cylinder and through the openings. Reciprocably mounted within each of the cylinders 67 is a can 55 chuck plate 69 carried at the upper end of a chuck spindle 70. This spindle vertically reciprocates through a packing gland 71 provided at the lower end of the cylinder 67 and held in position by a packing nut 72. The chucks and their 60

spindles are designed to have a sequence of operation which will be hereinafter described.

The turret sealing plate 62 is secured to a hub 73 mounted upon a vertical shaft 74 and adapted to rotate therewith. The turret sealing plate 62 is held in intimate contact with the lower face of the floor 57 so that there will not be an opportunity for the vacuum to be broken within a vacuum cylinder 67 after the openings 63 in the turret and the various openings such as 58 in the floor are out of register.

Each of the vacuum cylinders 67 is formed at its lower end with a drain duct 75 to which the body 76 of a drain valve 77 is secured and by which the particular cylinder may be drained of accumulated moisture. Mounted within the valve structure is a rotating valve member 78 of the spigot type having a tapered face fitting against a tapered seat and being held in position by an expansion screw 79. Valve rotating means 80 are provided at the lower end of each of the valves. This means includes a pair of pins 81 disposed at right angles to each other and extending radially from the axis of the valve. These pins successively strike a trip pin 82 adjustably held in a bearing 83 by a set screw 84. There are two of these pins as indicated in Fig. 10; pin 82 acting to open the valve and pin 82' acting to close it after the draining operation has been completed.

The seaming head structures at the two seaming stations 17 and 18 are substantially identical save for the fact that the seaming rolls in the first station make the initial curl of the seam and the seaming rolls at the second station finish the curl and close the seam.

The seaming heads are of the general type shown in my Patent No. 1,787,369, issued December 30, 1930 and entitled "Double seaming machine". This head structure generally includes a spindle 85 extending vertically through spaced bearings 86 and 87, at the lower end of which a centering chuck plate 88 is secured and is intended to seat within the recess of the cap of a can. This chuck plate is positioned within a centering bell 89 and around which bell a plurality of seaming rollers 90 are arranged and mounted upon pivoted levers 91 swinging on horizontal pivot pins 92 so that the rollers may be swung toward and away from the edge of the can. The upper ends of these levers carry cam rollers 93 which seat within the groove of a face cam 94. The face cam 94 is movable in a manner to be hereinafter described.

The bell structure upon which the levers 91 are pivoted is supported upon a sleeve 95 which extends upwardly through the bearings 86 and 87 and telescopes over the spindle 85. The sleeve is fitted with a gear pinion 96 in mesh with a driving gear 97 driven in a manner to be hereinafter described. Telescoping over the sleeve is a cam sleeve 98 carrying the cam 94 which cam is driven thereby at a different speed from that of the bell 89. This drive is produced by a pinion 99 mounted upon the sleeve 98 and in mesh with a gear 100. These gears are secured upon a vertical shaft 101 extending upwardly through a bearing 102 and fitted at its upper end with a pinion 103. Pinion 103 is beveled and meshes with a bevel driving gear 104. This gear is mounted upon a horizontally extending jack shaft 105 disposed in bearings 106 and 107 at the top of the machine.

A clutch structure 108 upon the jack shaft provides a driving connection with a pulley 109 which

is normally freely rotated upon the shaft 105. Disposed parallel to the shaft 105 and supported thereabove in bearings 110 and 111 is a manually operated shaft 112 carrying a hand wheel 113. This shaft is fitted with a pinion 114 normally out of mesh with a gear 115 and held in this position by a lock pawl 116 which engages a shoulder 117 on the shaft 112. When the pawl is moved to a non-obstructing position the shaft 112 may be shifted longitudinally to bring the pinion 114 and gear 115 into mesh and to make it possible for the operator to turn the jack shaft 105 and thus manipulate the entire mechanism for adjustment and repairs without power operation.

It is understood that while one of the double seaming heads and its driving mechanism has been described that the reference applies equally to both heads, since their construction and operation is substantially identical. Attention is directed however, to one apparent difference, and that is that the levers 91 of the seaming head at station 18 are longer than the levers shown at the first station. This being provided to obtain a greater purchase upon the rollers and to thus increase the pressure of the final rolling operation.

The machine is fitted with a main vertical driving shaft 118 which is provided with a bevel gear 119 at its upper end. This gear being in mesh with a bevel pinion 120 mounted upon the jack shaft 105. The vertical shaft 118 is mounted in bearings 121 and 122 and 123. Upon the lower end of the shaft 118 and here shown as beneath the base 124 is a gear 125 in mesh with a gear 126 carried upon a stub shaft 127. This gear is in mesh with first and second seaming operation gears 128 and 129 respectively. Disposed adjacent the drive shaft 118 is a detainer cam shaft 130 which is provided with a gear 131' in mesh with a gear 132' upon the vertical drive shaft 118. The lower end of the cam shaft 130 carries the driver 131 of a Geneva motion gear set and which is designed to intermittently operate a driven element 132, the structure being particularly shown in Figs. 4 and 5 of the drawings. Attention is particularly directed to this Geneva gear set since by its use numerous peculiar advantages of considerable value in the present machine are obtained, and a great many variable intermittent motions may be produced in machines of any type. In intermittently operating machinery it is necessary to set a mass into motion and to thereafter bring it to rest, the period of movement being definite and usually causing the machine to start and stop with a jerk imparting undesirable strain and wear to all of the parts. In the usual type of Geneva motion the periods of acceleration and deceleration are non-variably fixed. With the structure here disclosed the driving speed imparted to the driven element 132 may be varied at any point during the driving operation and may be positively established so that varying speed ratios within the limits of the machine may be rapidly and accurately obtained.

The driver in the present instant includes the cam disc 133 secured to the shaft 130 and which is characterized by having diametrically opposed arcuate cut away portions 133' in the opposite edges agreeing in arc and radius with the circumferential edge of the driven member 132. Slidably mounted above the cam 133 is a detainer 134 which extends transversely of the longitudinal center of shaft 130 and carries rollers 135 and 136 at its opposite ends. These rollers project downwardly and are parallel to shaft 133 around which they rotate. The rollers extend in-

- to a cam groove of a detainer arm cam 137. The cam groove 138 in the cam 137 may be of any desired configuration in the plane of the travel of the rollers so that as the rollers travel along it 5 the detainer arm 134 may be shifted transversally of the axis of the shaft 130. The cam 137 with its groove 138 does not completely circumscribe the shaft 130, but is cut away on one side to accommodate the driven cam 132 so that from the 10 end of the cam 139 to the end 140 of the cam groove 138 a roller 135 or 136 may travel in radial groove 141 of the driven cam 132. This driven cam is mounted upon a vertical shaft 142 which will hereinafter be described.
- 15 During the course of travel of the roller 135 or 136 which may at the moment be in engagement with the radial slot 141 of the cam 132 the other roller of the set mounted upon the driven arm 134 will be traveling along the cam groove 138.
- 20 If the cam groove describes a path along variable radii with relation to the shaft 130. As for example, the roller 135, shown in Fig. 5 of the drawings will cause the roller 136 to pursue a path along radii varying in lengths of inverse ratio to 25 that of the radii of the path along which the roller 135 is moving. It will, therefore, be seen that in the present instance, while the period of intermittent motion is represented by a half turn of the shaft 130 and the arcuate length of the intermittent rotation of the shaft 142 is here shown as being 90°, the driven cam 132 may be impelled at varying speeds during its period of movement and within the limits of the possible variation in the lengths of the radial arms formed 30 by the detainer arm 134 as this arm may shift transversally of the rotating axis of the shaft 130. In the present design the cam groove 138 is laid out so that as a detainer arm roller enters the radial slot 141 in the driven cam 132 it will immediately pursue a course along a progressively 35 shortened radii by gradual acceleration of the driven mass, after which it will assume a path of travel along its normal concentric arc at a relatively higher speed. It is also evident by such an arrangement the driving speed may be progressively decreased at the end of the driving period, 40 but in the present case other novel means are provided for damping the momentum of the mass and decelerating it as it comes to rest.
- 45 The shaft 142 extends upwardly from a lower bearing 143 and through an upper bearing 144. At a point intermediate its length a gear 145 is secured upon it, which gear is in constant mesh with a turret gear 146. The turret gear is formed 50 around the circumferential edge of the turret sealing plate 62, which moves beneath the floor 55 of the vacuum chamber.
- Means have previously been described for 55 progressively accelerating the driven mass of the machine, and means will now be described for progressively decelerating the mass which in this structure is particularly shown in Figs. 4 and 7 of the drawings, where it will be seen that the turret gear 146 is in mesh with a connecting rod gear 147. This pinion is keyed upon a vertical shaft 148 which is rotatably supported in a bearing 149. The lower end of this shaft carries a lever 150 secured to a connecting rod 151. This 60 rod extends horizontally through the side wall of the base of the machine and connects at its outer end with a piston 153. The piston is reciprocably mounted within a cylinder 154 and is provided at its outer end with a check valve structure 155. This structure includes a poppet valve 156 adapted 65 to close under compression within the cylinder and to be yieldably held upon a tapered seat 157 by a compression spring 158 disposed around the valve stem 159 and interposed between its cage 160 and a nut 161. The piston is suitably packed so that when it is drawn inwardly suction would be created within the cylinder 154 to open the valve 156 and so that when it is forced outwardly the valve will close permitting the air to pass outwardly through a relief opening 162. The relief opening 162 is relatively small in area as compared with that of the opening in the valve seat 5 so that on the stroke of the piston 153 away from the cylinder head, this opening will not provide sufficient air to permit the piston 153 to move without drawing the valve 156 away from its seat, and will on the other hand provide sufficient relief on the opposite stroke of the piston to permit the piston to gradually move to its outer position as checked by the retarded exhaust of air. The gear ratio existing between the turret 20 gear 146 and the connecting rod gear 147 is such as to cause a complete revolution of the connecting rod gear 147 during each interval of intermittent operation of the machine. The crank 150 is so set as to insure that during the initial 25 stage of operation of the machine, as brought about by the Geneva motion previously described, the piston will be on suction stroke and thus offering negligible resistance to the motion of the mass, and on compression stroke at the conclusion of the 30 operation to cushion and decelerate the motion of the mass without causing the strain of a sudden stop to be imposed upon the driving gears alone.
- Between intervals of intermittent operation the turret 146 is brought to rest with certain of the 35 openings 63 in register with the openings 58, 59, 60 and 61 in the floor 57, thus making it possible for simultaneous movement of four cams to move at once through the various registering openings and in a manner to be hereinafter described.
- 40 The cam feed star wheel 14 by which the cans are introduced into the machine and removed therefrom is driven from the shaft 142 by a gear 163 in mesh with a gear 164 upon the shaft 37 which shaft carries the star wheel 14. This wheel 45 will therefore be intermittently operated in synchronism with the rest of the driving mechanism. Disposed above the star wheel 14 and over the opening 58 in the floor is a pusher disc 165 which acts to follow the can down the pocket of the 50 star wheel and through the opening 63 into the vacuum cylinder 67 therebeneath. This disc is mounted upon a reciprocating stem 166 secured within a bearing 167 and fitted at its upper end with a pivotal connection 168. Rocker lever 169 is 55 secured to the pivot 168 and mounted upon a fulcrum pin 170. The opposite end of the lever indicated at 171 is provided with a roller 172 extending into a groove 173 of a barrel cam 174. This cam is fixed upon and rotates with the vertical driving shaft 119. The sprocket chain 29 is driven from the shaft 118 by a beveled pinion 175 meshing with a complementary gear 176 upon a shaft 177 and which carries a sprocket 178. The chain passes around this sprocket and over suitable sprockets at the opposite ends of its horizontal run, one of which is indicated at 179.
- 55 The cans 23 follow a circular path of travel around the axis of the turret sealing plate 62 and the shaft 180 upon which it is mounted. During 60 this course of travel the can moves from the inlet opening 58 in the floor 57 where it is dropped vertically into the cylinder 67 in register therewith and onto the chuck plate 69 which at the time the can is delivered will be in its uppermost 65 position.

position to receive the can, and lower it to a point where its upper edge will be below the plane of the upper face of the turret, after which the can will move beneath the floor within the sealed vacuum cylinder 67 until the cylinder registers with the opening 59. The can is then raised at the seaming station 17 and then lowered to pass beneath the floor 57 to the second seaming station 18 where it is again raised for a seaming operation. The can is then lowered and the turret moved with the can beneath the floor until it registers with the opening 61 in the floor where it is elevated its full height and introduced into a pocket of the star wheel 14 to be carried from the machine between the guide tracks 181 and 182. It is necessary, therefore, to provide means for lowering the can at the various desired points in its intermittent path of travel and for raising the can at these points. This mechanism includes arcuate cam track 183 along which rollers 184 may travel in a circular track. As particularly shown in Fig. 13 of the drawings, this track is interrupted at seaming stations 17 and 18 by vertical spurs 185 and 186 respectively, and at the inlet opening 58 is formed with a vertical portion of greater length than the height of a can indicated at 187. The track 183 then continues at an elevated plane as indicated at 183' and drops to the level of the track portion 183 along a vertical portion 188 at the outlet opening 61 through the floor.

For convenience in reference the station of the inlet opening is here indicated as A, the first seaming station as B, the second seaming station 35 as C and the outlet station as D.

When the rollers 184 of the spindles are in register with the spurs 185 and 186 in the can groove 183 a cross-head 189 engages them and moves them simultaneously vertically. This cross-head 40 is operated by a simple lever 190 mounted upon a fulcrum pin 191.

The lever 190 carries a cam roller 192 which engages a cam groove 193 in a drum cam 194, and by which the cross-head 189 is vertically 45 shifted. This cam is mounted upon a cam shaft 195 driven from the gear 126 through a gear 128 mounted on the shaft.

At the stations A and D, which are represented by the spurs 187 and 188, the chucks of the registering vacuum cylinders move alternately. That can be understood when it is remembered that at station A a can is lowered into a vacuum cylinder and simultaneously at station D a can is elevated and ejected therefrom. This operation is accomplished by an oscillating cross-head 50 of the simple lever order indicated at 197 and which is mounted upon a pivot 198 intermediate its ends. This lever is oscillated by a cam lever 199 mounted upon a pivot 200, and having a lever 60 projection carrying a roller 201. This roller engages a groove in a barrel cam 202 mounted on a shaft 118 of the machine. Lower chuck spindles 70 extend downwardly through bearings 203 carried upon a lower turret disc 204. This disc 65 is mounted upon the turret shaft 180 which shaft is supported upon a thrust bearing 204' carried by a bracket 205. A sleeve 206 is mounted upon the shaft and is formed with a plurality of longitudinal grooves 207 which receive guide fingers 208 projecting radially from the chuck spindles 70 and from their bearings 209 which extend through the spindles. The outer ends of the bearings 209 carry the rollers 184 and the fingers 75 208 hold the chuck spindles against rotation and

cause the rollers to remain in proper register with the cam grooves.

In operation of the present invention, cans are delivered to the feed table 19 in a continuous flow and are there encountered by yieldable retarding finger 24 and the timing star wheel or cam 21. The cans will be gradually separated to enter the machine in successive spaced relation to each other and will thereafter be positively fed at an accelerating speed by the fingers 26. The cans will then pass onto the floor 31 where they will be engaged by flights 32 of the chain 29 and will be carried forwardly in spaced relation to each other between the guide rails 33 and 34. As a can reaches the arcuate track portions 35 and 36 the pusher 44 will engage the can and shift it from the end of the trackway into register with the pocket 39 on the star wheel 14.

Attention is directed to the fact that prior to the delivery of the cans to the machine here described, the caps have been placed upon the cans and have been temporarily clinched into position. The uncurled cap will therefore have a greater diameter than the completely seamed cap which is mounted on the bottom of the can; thus it has been necessary to place the pockets 29 obliquely with relation to the vertical so that there will be clearance for the upper end of the can as it is fed downwardly through the table into a vacuum cylinder 67 as indicated particularly in 30 Fig. 12.

When the can is moved into the pocket 39 the star wheel 14 rotates one-quarter of its revolution, thus moving the can to station A indicated in Fig. 13 of the drawings. As the can approaches this station it will move over a relatively thick floor plate 49 and will drop approximately $\frac{1}{8}$ " through an opening 58 in the floor 57 to rest upon the lower chuck plate 69. At this time the star wheel 14 will come to rest and the can will slide 40 downwardly from its pocket 39 and will be lowered into the vacuum cylinder 67 as supported upon chuck plate 69 and as lowered by the chuck spindle 70. This lowering operation is brought about by oscillation of the cross-head lever 197 45 in a manner previously described. When the can has moved to its lowermost position its top will be below the level of the floor 57. The turret 16 carrying the various vacuum cylinders will then be set in motion by the Geneva gear structure, particularly shown in Figs. 4, 5, and 6 of the drawings, and due to the special design of this gearing the inertia of the mass will be gradually overcome until the can has moved substantially half of its increment of movement. During this first 55 half of its movement the turret will act to draw the piston 153 outwardly from the cushion cylinder 154 and during the second half of the movement the piston 153 will be forced inwardly 60 against compression of the fluid within the cylinder and the controlled exhaust therefrom. The effective action of the cushioning structure which includes cylinder 154, may be varied by varying the exhaust port area, and variation in the rate 65 of travel of the turret as controlled by the Geneva gearing, may be definitely established by an interchange of cams 137 having grooves 138 of different configurations.

As previously explained in the present case, there are seven can pockets in the turret sealing plate 62 and it will therefore be necessary for the can turret to move in increments of 1/7th of its circumference.

By reference to Fig. 14 of the drawings it will be seen that the face of the turret sealing plate 75

62 is formed with an annular oil groove 215 with which a plurality of lateral grooves 216 communicate. These grooves extend inwardly across the face of the plate between the openings 5 for the can pockets and at an angle to the radius of the plate. The grooves are pitched to cause their forward and outer ends to move in advance of the remainder of the grooves, thus tending to draw oil from the annular groove 215 and throughout the length of the lateral grooves 216. In this manner a film of oil will be formed entirely across the surface of the plate and will prevent unequal wear between the sealing surfaces which might otherwise be occasioned due to 10 the fact that the circumference of the plate will travel at a higher lineal rate of speed than the center area. This insures that there will be an hermetic seal at all times around the pockets into which the cans are acted upon by vacuum. 15 Attention is also directed to the fact that the present machine may be readily adapted for use of cans of different heights. This adjustment is afforded by set screws 219 which are carried in bosses of the track 183 and act upon the guide 20 rods 220, as particularly shown in Fig. 2 of the drawings. It is also provided that the operating mechanisms for causing reciprocation of the cans may be adjusted as particularly shown in Fig. 13 25 of the drawings, where it will be seen that the walking beam 221 is fitted at its opposite end with adjustable nuts 222 and 223 which carry adjusting links 224 and 225. These links articulately connect at 226 with the chuck spindles 70 so that by moving the nuts 222 and 223 inwardly 30 and appropriately adjusting the turnbuckle links 224 and 225 the position of the lower chuck discs 69 may be varied as well as the stroke of the pistons. 35

The first move of the can after leaving station A will be beneath the table where vacuum begins to form. The second move will bring it to station B, which is the first seaming operation station. Here the can will be elevated by the cross-head 189 and the kindred mechanism to place 40 the can and cap in seaming relation to the head of the seaming unit 17. After a seaming operation has been completed, the can is again lowered and moves beneath the table to an intermediate position between stations B and C, still 45 connected with vacuum in chamber by means of duct 6, and when again moved, moves into register with an opening 58 in the floor 57 so that it may be lifted to the seaming head of the second seaming unit 18. 50

During the time the can is within the pocket and the vacuum cylinder 67 is closed beneath the table 57, a condition of partial vacuum is created within the vacuum cylinder tending to evacuate the can as far as air and other gases are concerned. Such periods of evacuation take place 55 between stations A and B and also between stations B and C. The general arrangement of the vacuum pump and the suction lines is indicated in Fig. 15 of the drawings, where it will be seen that a vacuum pump 210 is provided and connects with a manifold 211 which in turn communicates with the vacuum cylinder 67 through suction lines 212 and 213. After the completely sealed can is lowered into its vacuum cylinder 67 60 at the second seaming station C it is moved around to the final station D where it is to be ejected from the machine. During this period of travel there is no vacuum action upon the cylinder, and it may be necessary to drain the cylinder to remove extraneous moisture. This is ac- 65

complished by causing the drain valve structure 77 to pass pin 82 at which time the valve will be opened to permit moisture to drain from the cylinder 67. When the cylinder with its valve moves onwardly toward the star wheel 14 it will encounter pin 82' which rotates and closes the valve. 70

When the cylinder with the can reaches the final station D it will be lifted from the vacuum cylinder by the lower chuck 69 and will be carried up onto the relatively thin floor plate 50 as the star wheel moves and may thereafter be carried away from the machine by any suitable method. 75

It will thus be seen that the structure here disclosed provides a vacuum double seaming closing machine of novel design, and which though intermittent in operation may move rapidly to accommodate a relatively large flow of cans and will perform its various operations upon them with a minimum amount of wear and tear upon the machine, and in a substantially novel and vibrationless manner. 10

While I have shown the preferred form of my invention, as now known to me, it will be understood that various changes may be made in combination, construction, and arrangement of parts by those skilled in the art without departing from the spirit of my invention as claimed. 15

Having thus described my invention, what I claim and desire to secure by Letters Patent is:—

1. A machine for double seaming cans in vacua which comprises a first seaming station, a second seaming station, a vacuum compartment enclosing said stations the floor of which compartment is formed at each station with an opening through which a can may be lifted, a rotary turret moving beneath said floor and having a sealing plate in contact therewith, said turret being formed with a plurality of can pockets rigidly carried by the turret and having openings through the sealing plate which will be successively brought to register with the openings in the bottom of the compartment, means in the various pockets for receiving a can and for raising or lowering it with relation to the pocket, and synchronous driving means whereby the turret may be registered and the cans will be raised and lowered with relation to the seaming stations and the successive seaming operations there performed in vacua. 40

2. A machine for double seaming cans in vacua which comprises a first seaming station, a second seaming station, a vacuum compartment enclosing said stations the floor of which compartment is formed at each station with an opening through which a can may be lifted, a rotary turret moving beneath said floor and having a sealing plate in contact therewith, said turret being formed with a plurality of can pockets rigidly carried by the turret and having openings through the sealing plate which will be successively brought to register with the openings in the bottom of the compartment, means in the various pockets for receiving a can and for raising or lowering it with relation to the pocket, and synchronous driving means whereby the turret may be registered and the cans will be raised and lowered with relation to the seaming stations and the successive seaming operations there performed in vacua, and means disposed exteriorly of the vacuum compartment to feed cans successively to the pockets of the turret after which they will be lowered within the turret pockets to a point beneath the floor of the compartment and thereafter moved beneath this floor to the first seaming station. 50

3. A machine for double seaming cans in vacua which comprises a first seaming station, a second seaming station, a vacuum compartment enclosing said stations the floor of which compartment is formed at each station with an opening through which a can may be lifted, a rotary turret moving beneath said floor and having a sealing plate in contact therewith, said turret being formed with a plurality of can pockets carried by the turret and having openings through the sealing plate which will be successively brought to register with the openings in the bottom of the compartment, means in the various pockets for receiving a can and for raising or lowering it with relation to the pocket, and synchronous driving means whereby the turret may be registered and the cans will be raised and lowered with relation to the seaming stations and the successive seaming operations there performed in vacua, said synchronous driving means including a variable mechanical movement whereby the turret will be intermittently moved to place its pockets in successive register with the seaming stations and will move at a predetermined variable rate of speed.
4. In a machine for operating on sanitary cans which cans have a cap temporarily clamped upon them and which machine includes a floor over which cans move, means for feeding a can to an opening in the floor, means by which the can is lowered through the opening, a star wheel having arcuate pockets to receive the cans and move them into register with said openings, said pockets being disposed at an inclination to the vertical whereby clearance will be provided for the enlarged end of the can carrying the clamped cap as the star wheel moves to register with said opening.
5. In a machine of the class described including a conveyor having pockets into which cans may be fed, the lower ends of which pockets are closed, drain valves one for each of said pockets, means carrying the can within a pocket to and away from a vacuum station in a cycle of operation and means whereby the valves will be successively opened as the respective pockets conclude a cycle of operation and successively closed as the pockets begin a new cycle of operation.
6. In a machine of the class described, comprising a horizontally rotating turret formed with a plurality of can pockets, the lower ends of which are closed, a plurality of drain valves one for each pocket, a lower chuck plate vertically reciprocating in each pocket to receive a can and lower it into the pocket and thereafter to lift the can so that it may be ejected from the pocket, and trip means acting to open the valve of a pocket at the approximate time the can is ejected therefrom and to close the valve of said pocket at the approximate time a can is lowered thereinto.
7. In a machine of the class described, a rotary turret formed with a plurality of can pockets therein and spaced circumferentially thereof, chuck plates within each pocket, a chuck spindle extending downwardly from each of the pockets for carrying a chuck plate mounted within a pocket, cam tracks extending along the path of travel of the turret and said chuck spindles, means operatively connecting said chuck spindles and the cam track whereby the spindles will be reciprocated at points in their travel, and means for setting the cam tracks so that the stroke of movement of the chuck spindles may be adjustably set.
8. In a machine of the class described, a rotary turret formed with a plurality of can pockets therein and spaced circumferentially thereof,
9. In a machine of the class described, a rotary turret formed with a plurality of can pockets therein and spaced circumferentially thereof, chuck plates within each pocket, a chuck spindle extending downwardly from each of the pockets for carrying a chuck plate mounted within a pocket, cam tracks extending along the path of travel of the turret and said chuck spindles, means operatively connecting said chuck spindles and the cam track whereby the spindles will be reciprocated at points in their travel, means for setting the cam track so that the stroke of movement of the chuck spindles may be adjustably set, and positive acting means to positively move the spindles with relation to the cam track at certain points in their travel.
10. In a vacuum machine, a vacuum compartment, means connected therewith for evacuating the same, said compartment being formed with an opening, a turret plate formed with can openings, a conveyor associated therewith and formed with pockets communicating with the opening in said turret plate whereby a condition of vacuum will be created within the pocket when the openings in the turret plate and the compartment wall are in register, and means for creating a uniform film of oil between the face of the turret plate and the contacting face of the compartment whereby an hermetic seal will be continuously created.
11. In a vacuum machine, a vacuum compartment, means connected therewith for evacuating the same, said compartment being formed with an opening, a turret plate rotating on an axis and in facial contact with the wall through which the opening is formed and having an opening adapted to be brought to register therewith, a can receiving member carried by the turret plate and communicating with the opening in said turret plate whereby a condition of vacuum will be created within the can receiving member when the openings in the turret plate and the compartment wall are in register, and means for creating a uniform film of oil between the face of the turret plate and the contacting face of the compartment whereby an hermetic seal will be continuously created, said means comprising a circular oil groove formed upon the contacting face of the turret plate adjacent its circumferential edge, and a plurality of lateral grooves formed upon the contacting face of the turret plate and extending diagonally across the diameter of the plate at an angle counter to the direction of movement of the plate.
12. A machine for double seaming cans in vacua which comprises a vacuum chamber having an opening in the floor thereof through which a can may be projected, a can seaming unit housed within said vacuum chamber, a turret rotatable beneath said vacuum chamber and having an up-

- per surface forming an air tight seal with the under face of said vacuum chamber and with openings through said turret face to register consecutively with the opening in the floor of the 5 vacuum chamber, said turret being formed with can pockets one associated with the turret at each of said openings to receive a can to be seamed within the vacuum chamber and means within said pockets for successively raising and lowering 10 a can through the opening in the pocket and the opening in the vacuum compartment when said openings are brought to register.
13. A machine for double seaming cans in 15 vacuum which comprises a vacuum chamber, a floor for said chamber having a can opening therethrough, a seaming head above said opening, a turret moving below said floor and having an upper wall in surface contact with the floor of the vacuum chamber, said turret being formed 20 with a plurality of can receiving members adapted to successively register with the opening through the floor of a vacuum compartment, means for simultaneously delivering a can and its cap to said individual can receiving members of the 25 turret, means for receiving the can within said members to lower and raise the can, means for driving the turret to bring can receiving members and a can carried thereby into successive register with the opening through the floor of the vacuum 30 chamber, and means operating in synchronism to raise said can through the opening into operative relation to the seaming head, maintain the can in said position during the seaming operation, and retract the can into the can receiving 35 member after which the turret advances to a new position.

14. A machine for double seaming cans in 5 vacuum which comprises a vacuum chamber, the floor of said chamber being formed with a can receiving opening, a seaming head within said chamber, a turret below said floor and having an upper wall in continuous surface contact with the 10 underside of said floor whereby to maintain a vacuum seal between said contacting faces, said turret being formed with a can receiving pocket opened at its upper end and adapted to be moved to a point of register with the opening in the floor of the vacuum chamber, means for moving 15 said turret to and from a point of register with the can receiving pocket and the opening in the floor of the vacuum chamber while maintaining the contiguous faces of said floor and turret in continuous contact whereby the vacuum within the vacuum chamber is maintained, means within 20 said can receiving pocket to lower a can into said pocket and to raise it to an operative position with relation to the seaming head when the can receiving member and the opening in the pocket are in register, and to then retract the can through the opening in said floor at the conclusion 25 of said seaming operation, and driving means operating in synchronism to intermittently move the can receiving member of the turret to and from the seaming station, means operating in synchronism therewith to intermittently move the can lifting and retracting means, and 30 means for operating the seaming head when a can has been operatively disposed relative thereto.

HENRY L. GUENTHER. 35
